CONTAINER AND QUICK DETACHABLE
SEALING CAP

Alfred S. Harkness, Jr., Narberth, Pa.

Application June 6, 1933. Serial No. 674,531

10 Claims. (Cl. 221—60)

My invention relates to improvements in a container having a quick detachable sealing cap, and particularly to containers of the flexible tube type, for shaving cream, tooth paste, paint, cement, and the like.

The object of my invention is to provide a container and a sealing cap arranged to form a perfect seal for the tube, without the use of cork, or rubber, disks located between the container 10 and the cap.

A further object is to provide a cap which can be readily operated with one hand when attaching and removing it from the container.

A further object is to provide a container with 15 a head having a side discharge opening, and provide the head and the cap with coacting sealing facing surfaces for tightly closing said opening.

A further object is to provide a container 20 with a head having a side opening, and a cap comprising pivotally associated jaws, and also provide the head with means for insuring the jaws being placed upon the head in the proper radial position for sealing the discharge opening.

A further object is to provide the cap with 25 stops for limiting the opening movement of the jaws, and also provide the container with an elliptical head, so that the cap cannot be placed on the head unless the pivotal axis of the jaws 30 is nearly parallel with the longer axis of the elliptical head, whereby the spring actuated jaws will properly adjust themselves upon the head for closing the discharge opening.

Referring to the accompanying drawing;— Fig. 1 is a side elevation of a portion of a container and cap, embodying my invention.

Fig. 2 is a front elevation of the cap, detached.

Fig. 3 is an inverted plan view of the cap.

Fig. 4 is a plan view of the cap.

Fig. 5 is a vertical section of the cap, as on line 5—5 Fig. 1, showing the container in elevation.

Fig. 6 is a vertical section on line 6—6 Fig. 5.

Fig. 7 is a sectional view of the cap, with the jaws open, and a front elevation of the container.

Fig. 8 is a plan view of the container and 50 showing the jaws of the cap in dotted lines.

In the accompanying drawing in which like reference characters refer to like parts, 10 represents the container of the flexible metal tube type. A head 12 is formed upon the container 55 and is provided with an elongated slit forming

a discharge opening 13. The head is formed with a protruding convexed, outer portion 14. Said head is also provided with an annular recess 15, and an annular collar, or shoulder 16. The head 12 is elongated as shown in the plan view Fig. 8.

The opening 13 of the head extends laterally relatively to the longitudinal axis extending through the head and the container, as shown in Fig. 6, and said opening is located on the shorter axis of the elliptical head as shown in Fig. 8. The convexed head 12 is provided with a facing surface, or valve seat 17 surrounding the opening 13.

The cap 20 comprises two members, 21 and 22, pivotally secured together by a shaft 23. Said members are formed with jaws 25 and 26, and handles 27 and 28. A spring 29 embraces the shaft 23 and acts upon the handles and tends to close the jaws together. The handles are 75 provided with lugs forming stops 30 and 31, which engage for limiting the opening movement of the jaws.

The jaws 25 and 26 are provided with recesses 32 and 33, which recesses are formed with inner 80 convexed surfaces 34 and 35, which have the same contour as the facing surface forming the valve seat 17 on the head 12 and will tightly seal the opening 13, as shown in Fig. 6.

The jaws 25 and 26 are also provided with inwardly projecting lips 36 and 37 which embrace the shoulder 16 of the head and hold the cap upon the head, as shown in Fig. 6.

Fig. 7 illustrates that the stops 30 and 31 will engage and prevent the jaws opening sufficiently to allow them to embrace the head 12, when the pivotal axis, or shaft 23, is at right angles to the longer axis of the elliptical head 12, thus insuring the cap being placed upon the head so that a facing surface 34 or 35 will fully cover the opening 13.

Fig. 8 illustrates that, when the jaws 25 and 26, shown in dot and dash lines, are placed nearly in their proper radial position upon the elliptical head 12, the jaws will adjust themselves upon 100 the head, by the action of the spring 29, and properly seal the opening 13.

A container and cap constructed according to my invention can be readily operated, as the cap can be applied to, or removed from, the container 105 by pressing the handles 27 and 28 together, which can readily be done with the fingers of one hand, without holding the container in the other hand. The cap cannot be placed upon the head with the openings between the jaws extending 110.

over the discharge opening 13 of the head, which would permit the material to leak from the container. The elongated formation of the head insures the jaws being properly positioned radially upon the head, so that a facing surface of a jaw will cover the opening 13 of the head. The elliptical formation of the head forms cam surfaces against which the jaws are pressed by the action of the spring, which latter tends to turn the jaws upon the head so that the jaws will fully cover and tightly seal the discharge opening.

I claim:—

1. A container having a protruding head with an outer facing surface thereon, said head having a discharge opening through said surface, a cap comprising pivotally associated jaws, said jaws having corresponding recesses formed therein and arranged to receive said head between the jaws, and said jaws having facing surfaces forming the inner surfaces of said recesses and having the same contour as the contour of the facing surface of the head and arranged for sealing said discharge opening.

2. A container, a head upon the container, said head having a discharge opening located laterally relatively to the axis extending through the head and the container, a facing surface upon said head and surrounding said opening, a cap comprising pivotally associated jaws arranged for embracing the head, and a facing surface upon a jaw and having the same contour as said facing surface surrounding said discharge opening and arranged to seal said opening.

3. A container, a head upon the container, said head having a side discharge opening, a facing surface upon the head and forming a valve seat surrounding said opening, jaws pivotally joined together and arranged to embrace said head, and a facing surface upon one of said jaws arranged to seat upon said valve seat and close said opening.

4. A container, a head upon the container, said head having a side discharge opening, a facing surface upon the head and forming a valve seal surrounding said opening, jaws pivotally joined together and arranged to embrace said head, facing surfaces formed upon said jaws and having a contour corresponding to the contour of the facing surface forming the valve seal upon the head, and a spring operatively associated with the jaws tending to clamp the latter upon the head with a facing surface of a jaw upon said valve seat.

5. A container, a head upon the container, said head having a discharge opening located laterally relatively to the axis extending through the head and the container, a facing surface upon said head and surrounding said opening, a cap comprising pivotally associated jaws arranged to embrace the head, said head having an annular recess formed therein and located between the container and said opening, lips formed upon said jaws and projecting inwardly and arranged to occupy said annular recess, facing surfaces upon said jaws and having the same contour as the facing surface surrounding said opening, and a spring operatively associated with said jaws tending to close said jaws with a facing surface of a jaw upon the facing surface of the head surrounding said opening.

6. A container, a head upon the container, said head having a discharge opening formed through the same and extending laterally relatively to the longitudinal axis extending through the head and the container, jaws pivotally associated and arranged to embrace the head, a spring operatively associated with the jaws tending to close the jaws upon the head, and means upon the head and upon said jaws arranged for radially positioning the jaws upon the head with one of the jaws covering said opening.

7. A container, a head upon the container, said head having a discharge opening formed through the same and extending laterally relatively to the longitudinal axis extending through the head and the container, a pair of jaws, a shaft upon which the jaws are pivoted, a spring upon said jaws tending to close the jaws, and means upon the head arranged to engage the jaws and radially locate the jaws upon the head with the pivotal axis of the jaws at right angles to the radial position of said opening.

8. A container, a head upon the container, said head having a discharge opening formed through the same and extending laterally relatively to the longitudinal axis extending through the head and the container, a pair of jaws, a shaft forming a pivotal axis upon which the jaws are mounted, a spring upon the jaws tending to close the same, said head having an irregular form, and said jaws having recesses formed therein and having a form corresponding to the form of the head whereby the jaws will only receive the head in certain relative radial positions in which the pivotal axis of the jaws is out of alignment with the radial position of said opening.

9. A container, a head upon the container, said head having a discharge opening formed through the same and extending laterally relatively to the longitudinal axis extending through the head and the container, a pair of jaws, a shaft forming a pivotal axis upon which the jaws are mounted, a spring upon the jaws tending to close the same, said head having an elongated form, said jaws having recesses formed therein and having a form corresponding to the form of the head, and means upon said jaws forming a stop to limit the opening of the jaws to a distance less than the length of the head whereby the jaws will receive the head only when the pivotal axis of the jaws is nearly parallel with the longer axis of the head.

10. A container, an elongated head upon the container, said head having a side discharge opening upon the shorter axis of the elongated head, a facing surface upon said head forming a valve seat surrounding said opening, a pair of jaws, a shaft forming a pivotal axis upon which the jaws are mounted, a spring upon the jaws tending to close the same, said jaws having recesses formed therein and having a form corresponding to the elongated form of the head and arranged to seat upon said facing surface surrounding said opening for sealing the latter, and means upon the jaws forming stops to limit the opening of the jaws to a distance sufficient to receive the head only when the pivotal axis of the jaws is nearly parallel with the length of the elongated head.
